POCKET TURKISH PIPE

Filed Dec. 6, 1926.

UNITED STATES PATENT OFFICE

MAURICE ALLAND, OF ATLANTIC CITY, NEW JERSEY

POCKET TURKISH PIPE

Application filed December 6, 1926. Serial No. 153,034.

The object of the invention is to provide improvements in that class of articles used in the smoking of tobacco and the like.

It has long been the custom in certain countries such as Persia and Turkey to employ a so-called Turkish pipe in which the smoke from the burning tobacco, instead of being inhaled directly by the smoker, first passes through water which serves the triple purpose of cooling the smoke, adding moisture to it, and last and most important of all extracts from the smoke substantially all of the nicotine, which tobacco possesses to a large degree.

However, the usual types of "Turkish pipes" are much too large and cumbersome to be carried around even in those countries, while here in our western civilization such smoking articles to be feasible for commercial use must be of such size and construction as to permit them to be carried in the pockets of one's clothes, and also must provide for a suitable quantity of water to serve the above-mentioned functions in a container which can be readily emptied, cleaned and refilled without trouble, and without attracting undue attention.

Another object more specifically is to provide a smoker's pipe comprising the usual bowl and channelled stem, but with a depending, removable, water container, means for supporting said container in operative position, and a structure interposed between the lower inner portion of the bowl and the forward end of the stem whereby an indirect channel is formed, to insure the smoke-containing draft passing from the bowl, into the water within the container, and after being trapped above the surface of the water being adapted to enter the intake end of the stem channel.

A further object is to provide a construction by means of which these improvements are adapted to a cigar or cigarette holder in which an intermediate portion of the stem channel is stopped by a transversely extending partition, through which a channel is deflected downwardly beneath the surface of the water in a container suspended therebelow, a second channel leading from within

said container above the surface of the water and thence toward the outlet or lip-engaging end of said stem.

In addition to the foregoing general objects, there is provided a specially designed structure for satisfactorily mounting the apparatus in unitary relation with a pipe, cigar or cigarette holder, whereby low cost of production is possible, efficiency in operation is insured, and easy cleansing of the several parts is readily accomplished.

With these and other objects in mind, the invention comprises further details of construction and operation fully described in the following specification when read in conjunction with the accompanying drawings, in which Fig. 1 is a side elevation of one embodiment of the invention as applied to a smoker's pipe; Fig. 2 is a vertical longitudinal section of the same; Fig. 3 is a section of the pipe taken in the direction indicated by line 3—3 of Fig. 2; Fig. 4 is a fragmentary sectional view of a modified form of the device; Fig. 5 is a vertical longitudinal section of the invention as embodied in a cigar or cigarette holder; and Fig. 6 is a vertical section of a fragmentary portion of the same on the line 6—6 of Fig. 5.

Referring to Figs. 1 to 3, inclusive, a smoker's pipe is shown as comprising the usual bowl 1, suitably hollowed to provide a tobacco-receiving container 2, and provided with any desired shape of stem 3, terminated in a mouth-engaging end portion 4, and having a longitudinally extending channel 5, which at the bowl end is restricted to a relatively narrow inlet opening 6.

Instead of the bottom wall of the pipe bowl being imperforate, it is provided with a bore 7, in which is removably positioned an internally threaded cylinder 8, having a transversely extending partition 9, through which latter extends the fixedly secured upper end portion of a tube 10. The cylinder 8 is provided with a radially extending peripheral flange 11, normally bearing against the upper surface of a shoulder 12 in the bore 7. Said cylinder is also provided with an upwardly extending externally threaded cylindrical flange 13, to which is secured a prefer-

90

95

100

ably downwardly tapering cap 14, having its upper portion open and surrounded by an undercut flange 15 which extends axially beyond an annular shoulder 16. A disc 17 having apertures 18 is normally snapped into the groove beneath said undercut flange, to provide a false perforated bottom for the container 2, and is provided unitarily with a depending ejector rod 18^a extending freely 10 through and slightly beyond the lower extremity of the tube 10.

Within the lower portion of the cylinder 8 there is removably secured a cylindrical member 17^a, provided with a bore 18^b through 15 which the tube 10 extends in spaced relation, said last-named member merging into a much larger inverted cup-shaped or bell member 19, which is normally fixed in operative position with respect to the pipe by means of a 20 pin 20, which connects them to prevent relative rotative movement.

The lowermost portion of the bell member 19 is reduced at 21 and externally threaded so as to receive in removable engagement, 25 the upper edge portion of a reservoir member 22, adapted to normally contain water 23, and provided at the upper portion of its periphery with a knurled radially extending circumferential beading 24. This reservoir is normally supported as shown in the drawings, and in this position, it will be noted, the lower end of the tube 10 extends well beneath the upper surface of the water, 30 while tobacco (not shown) normally fills the bowl above the upper surface of the disc 17.

In order to remove this disc and thereby cleanse the interior of the tube 10, the reservoir member is removed from the bell member 19 and the lower protruding end of the 40 ejector rod 18^a pressed upwardly, thereby releasing the disc from engagement with the undercut flange. Upon inverting the pipe the disc and rod will drop out and permit the ready cleansing of the tube 10 with a 45 pipe-cleaner or the like. On the other hand, when the several parts are in the relative positions shown in said drawings, the smoker upon drawing air inwardly through the stem channel 5 causes smoke from the tobacco in 50 the bowl to pass through the apertures 18 into the disc 17, and thence through the tube 10 beneath the water in the reservoir, whence it bubbles upwardly and is trapped within 55 the bell member 19, and is thence free to pass through the bore 18^b and through an aperture 25 in the cylinder 8, and through the narrow inlet opening 6 towards the discharge end 4 of the stem by way of the channel 5.

Referring now to Fig. 4, there is shown a 60 pipe comprising a cylindrical head 30, providing a tobacco-receiving bowl 31 and having a laterally extending integral stem 32, provided with an axially extending channel 33, leading from said bowl by way of a reduced bore 34. The lower portion of said

bowl merges into a downwardly tapering bore 35. Within said bore is a cylindrical member 37, having an enlarged downwardly opening space 38, terminating upwardly in a transversely extending partition 39, through which 70 extends and is fixed the upper end portion of a tube 40. The upper portion of the member 37 terminates in an externally threaded cylindrical flange 41, normally carrying a removable cap 42, having an enlarged aperture surrounded by an undercut flange 43, into which snugly fits a disc 43^a, having apertures 44 and a depending ejector rod 45, the latter extending freely thru and beyond the lower end of the tube 40 and being adapted 80 to be pressed upwardly to force said disc from the undercut flange 43, thereby opening the aperture in the cap 42 and making it possible to cleanse the tube 40.

The lower or under portion of the head 85 30 is hollowed out at 46 and normally receives a fixed liner member 47, the lower end of which extends freely beyond the surrounding portions of the pipe and is externally threaded to detachably receive the upper open end 90 portion of a reservoir 48, normally containing water 49, and provided with a preferably knurled beading 50, which facilitates the manual engagement of said reservoir for the purpose of detaching the same from the pipe. 95 On the other hand, the reservoir 48 may be secured directly to the lower or under portion of the bowl by being in threaded engagement therewith, instead of through the medium of the liner 47. In any event, the operation of this form of the device is the same as that hereinbefore described, the smoke from tobacco within the bowl passing through the apertures 44 in the cap 42 and thence through the tube 40, after which it bubbles upwardly 105 through the water 49 and is led through an aperture 51 in the wall of the tapering member 37, and thence through the channels 34 and 33 to the mouth-engaging end of the stem 32.

Referring now to Figs. 5 and 6, a cigar or cigarette holder is shown as comprising a stem 60, having a bore 61, leading from the mouth-engaging end towards a transversely extending aperture 62, beyond which a second bore 115 63 leads from said aperture to an enlarged cigarette or cigar-receiving recess 64. Normally positioned within the aperture 62 is a plug 65 having an aperture 66, normally communicating with the bore 61, and thence leading by way of a channel 67 into the upper portion of a bell-shaped member 68, open at its lower externally threaded end, except for a cup-shaped reservoir member 69 which is removably secured thereto and is provided externally with a preferably knurled beading 70 for manually engaging said reservoir and to facilitate its removal from the bell member 68.

Extending into the opposite side of the 130

plug 65 is a second aperture 70^a which communicates with a tube 71, which in turn extends freely through said bell member in spaced relation with the lateral walls of the latter, and beneath the surface of water 72 normally contained within said removable reservoir. A pin 73 extends radially from said plug and slidably engages within a recess 74 forming a lateral extension of the aperture 62 in the stem, for the purpose of preventing relative rotation of the bell member with respect to said stem. Furthermore, the uppermost portion of said plug is provided with an internally threaded aperture 75, which normally receives the threaded stem 76 of a retaining means, having a head 77, provided with recesses 78 for engagement with a spanner wrench or the like, the function of said last-named means being to retain the plug 65 and parts connected therewith in operative position as illustrated. The operation of this embodiment of the invention is likewise similar to that hereinbefore described with respect to Figs. 1 to 3, inclusive, but specifically provides for a smoker to draw through the stem 60, thereby causing smoke from a cigar or cigarette within the recess 64 to pass through the bore 63, the tube 71, beneath the surface of the water 72, and into the bell member 68, whence it is led by way of the bore 67 and cooperating bore 61 upward and through the mouth-engaging end of the stem.

Having thus described my invention, what I claim and desire to protect by Letters Patent of the United States is:—

1. A smoker's pipe, comprising a bowl opening through its bottom wall by means of a bore defined by circumferential shoulders at its opposite ends, a bell-shaped member positioned against the lower shoulder and having a neck extending upwardly into said bore, a cylindrical member within said bore and provided with a transversely extending partition having an aperture, said member and said neck being normally secured together detachably, a second cylindrical member having an enlarged end portion positioned against the upper of said shoulders and having a reduced portion extending into said bore and normally detachably secured to said first cylindrical member, a tube extending through the aperture in said partition to a point below the lower extremity of said bell-shaped member, a transversely extending apertured disc within said bowl removably supported by said enlarged end portion, and a rod carried by said disc and extending loosely through and to a point slightly below the lower extremity of said tube.

2. A smoker's pipe, comprising a bowl opening through its bottom wall by means of a bore defined by circumferential shoulders at its opposite ends, a bell-shaped mem-

ber positioned against the lower shoulder and having a neck extending upwardly into said bore, a cylindrical member within said bore and provided with a transversely extending partition having an aperture, said member and said neck being normally secured together detachably, a second cylindrical member having an enlarged end portion positioned against the upper of said shoulders and having a reduced portion extending into said bore and normally detachably secured to said first cylindrical member, a tube extending through the aperture in said partition to a point below the lower extremity of said bell-shaped member, a transversely extending apertured disc within said bowl removably supported by said enlarged end portion, a rod carried by said disc and extending loosely through and to a point slightly below the lower extremity of said tube, a wall of said first cylindrical member having an aperture below said partition, and a stem having a bore in communication with said last-named aperture.

In testimony whereof I have affixed my signature.

MAURICE ALLAND.
